UNITED STATES PATENT OFFICE.

ROBERT Z. DRAKE, OF OMAHA, NEBRASKA.

TAP BOLT AND OPERATING CAP THEREFOR.

Application filed October 2, 1922. Serial No. 591,730.

To all whom it may concern:

Be it known that I, ROBERT Z. DRAKE, a citizen of the United States, residing at Omaha, in the county of Douglas and State of Nebraska, have invented certain new and useful Improvements in a Tap Bolt and Operating Cap Therefor, of which the following is a specification.

This invention relates to a threaded bolt and a driver-cap therefor found to be particularly useful in bridge building, and useful specifically for securing planks to beams, girders or similar supports, and includes among other objects, the provision of a mounting of greater firmness and solidity than usual for the planks on said supports, so that vibration of parts will be practically eliminated, the particular means for mounting the planks being attended with less expense and adapted to be more quickly and conveniently performed than ordinary. Another object is to provide such a construction that repair work may be conveniently done and that workmen may operate while above instead of below the girders or beams, either when building or repairing a bridge. The invention also includes the provision of incising elements for the heads of the bolts, to facilitate countersinking in the planks, the shanks of the bolts having greater diameter than the threaded parts to facilitate operation when securing the planks to the beams or girders, and formed non-concentric with the threaded parts to cause a sidewise movement or crowding of the plank to form a complete roadway. While useful in connection with bridge construction, the device, of course, may be employed for other purposes.

With the above objects in view and others to be mentioned, the invention presents a novel construction, combination and arrangement of parts as described herein and claimed, and as illustrated in the accompanying drawings, wherein,—

Fig. 1 is a plan view of a tap-bolt. Fig. 2 is a bottom plan view of the same. Fig. 3 is a side view of the tap-bolt. Fig. 4 is a plan view of a driver-cap for the tap-bolt. Fig. 5 is a bottom plan view of the driver-cap. Fig. 6 is a side view of the driver-cap, a part of a tap-bolt also being shown partly in section. Fig. 7 illustrates a plank supported by and secured to a beam or girder by use of the tap-bolts. Fig. 8 illustrates a plurality of beams or girders

and a plank secured thereto by use of the tap-bolts.

Fig. 9 is a broken, plan view showing planks secured to girders. Figs. 10 and 11 show modified forms for the bolts. Fig. 10 is a side view of a bolt having a threaded part concentric with and of lesser diameter than its shank. Fig. 11 illustrates a bolt having a shank non-concentric with its threaded part. Fig. 12 is a view, partly in section, showing a part of a girder in side elevation with planks secured thereon by use of the threaded bolts. Fig. 13 shows a modified form for a bolt-head.

Referring now to the drawing, the invention, for convenience, is shown and described in connection with metallic beams or girders 10 which support the planks 11 of a bridge, but the invention is adapted for use in connection with beams or girders constructed of wood or other suitable material.

In order that the advantages above mentioned may be derived, I provide a tap-bolt 12, its head *a* being of disc-form and having peripheral recesses *b* opening on its top and bottom, a secondary recess *c* being formed in one of the walls of each recess *b* to open on the bottom of the head *a*, and segmental recesses or depressions *e* being provided which also open on the bottom of the head, each recess *e* opening on a recess *b* and having an inclined wall extending from a recess *b* to a recess *c* to form a cutting edge *f* extending diametrically from a recess *b* to the shank on the bolt.

While in the drawing, I have shown four recesses *b* together with four depressions *e* and four blades or edges *f* the particular number of the parts is not important, and they may be greater or less, depending upon the kinds of plank employed and whether the threads are fine or coarse, for the bolts.

It will be appreciated that if the bolts have threaded connections with the beams or girders or their flanges 13, suitable apertures 14 being formed in the plank for receiving said bolts, all work may be performed at the top of the bridge, this being a matter of great advantage when securing the planks to the girders or beams, and being a feature of convenience in repair work when the planks require replacing.

In order that this may be accomplished, and that the bolts may be rotated so that the heads *a* may be countersunk in the

2
planks and also that the bolts may be removed, I provide a driver-cap 15 for the tap-bolts, its upper side being provided with an angular head 16 adapted to be gripped by a wrench (not shown), the lower part of the cap being provided with lugs 17 corresponding in number to the recesses *b* of the disc-head *a*, each lug 17 being provided at its free end with a pair of opposed, horizontal catches or projections *d* the spacing and proportions of the recesses *b* being such that the lugs of the cap will readily enter said recesses *b* when the cap is applied to the heads *a* for rotating the bolts.

15 In operation, a tap-bolt 12 being inserted in an aperture 14 to enter a threaded aperture of a girder or its flange 13, the cap is applied to the head, *a*, and by use of a wrench, the cap, together with the bolt, may 20 be rotated. The parts are so proportioned that each lug 17 will engage a side wall of a recess *b* when the cap is rotated for moving a bolt, and therefore the stresses directed to the head *a* will be sustained by 25 the lugs coincidently and uniformly, this being a feature relating to durability, since liability to breakage of any of the lugs 17 will be reduced to a minimum. In practice, the tap-bolt may be rotated until its head 30 *a* will become countersunk, the blades or edges *f* operating to cut the fiber of the plank regardless of its density or hardened condition, to permit countersinking.

By referring to Fig. 2 it will be seen 35 that each blade *f* extends radially to a recess *c*, each recess *c* having a side wall as shown in Figs. 2, 3 and 6 obviously operating as a blade since it terminates at the bottom of the bolt's head the same, in this respect, as the 40 termination of a blade *f*, and while the side walls of recesses *c* are not disposed radially of the bolt's head they are each disposed in the plane of a blade *f*, and are adapted to cut into the wood when the bolt 45 is rotated.

It will be understood, of course, that chips or shavings, cut by the blades, will move in lines of least resistance, and since the depressions or recesses *e* are formed 50 outwardly divergent and with their greater area at the periphery of a bolt-head, the chips, during operation, will move outwardly toward the recesses *b*.

By use of the cap 15, the bolts may be 55 readily removed from the planks and from the beams or girders, this being a matter of convenience in the work of removing planks when they require replacement. During the operation of rotating a bolt, 60 the cap will not readily become detached from the head *a* since one of the projections *d* of each lug 17 may engage in a recess *c* or in a recess *e*, this being a matter of importance during operation, for otherwise the cap might become detached from

the bolt. Also the tap-bolts, in some instances may be inverted or may be disposed in a horizontal or inclined position, and the projections *d* for engaging in recesses *c* or *e*, as mentioned, permits operation regardless of the inclination of the tap-bolts. 70

Figs. 10, 11 and 12 illustrate modified forms for the bolts, considered to be within the scope of the invention, the bolt indicated at 18 having its body or shank *g*, threaded part *h* and disc-head *a* formed concentric with its axis *x*—*x*, the threaded part *h*, however, having a lesser diameter than the diameter of the shank, one of the advantages in the use of this bolt being that, in instances where the apertures in the plank have, comparatively, a greater diameter than ordinary, the upper part *g* of the bolt may fill the aperture *k* (Fig. 12) 80 in a manner to prevent water from entering therein; also the threaded terminal of the bolt, if of adequate length, may be conveniently inserted in the aperture of the beam or girder in instances when the aperture of a plank does not register, in a degree of exactness, with the aperture of a beam or girder. 85

The bolt indicated at 19 has a body or shank *g*' disposed with its axis *z*—*z* non-concentric with the axis *s*—*s* of its threaded part *m* and head *a*, the threaded part *m* having a lesser diameter than the body portion *g*', the advantage in the use of said bolt being that it will operate to move the 100 plank sidewise when rotated in the aperture *k*, its threaded part being in engagement with the beam or girder, the sidewise movement of the plank operating to crowd or press it against the edge of a plank adjacent thereto, to form a more complete roadway in instances when the plank is in a buckled or warped condition, or when the aperture *k* of the plank and aperture *n* of the beam or girder do not align with 105 exactness, when the plank is placed on the girder. 110

By use of the invention, the planks will remain firmly connected with the beams or girders. The heads of the bolts will not project above the surface of the roadway to cause injury. Also when the planks become worn, the bolts may be lowered, simply by rotating them, so that the heads 115 will not obtrude.

It is appreciated that the apertures *p* formed in a beam or girder may not be disposed at such distances from each other that they will register, with exactness, with the apertures *k* of the planks, and in such instances the bolts 19 will be found to be of great advantage. Also if the threaded part of the bolt 19 is of adequate length it may be inserted in an aperture *p* conveniently, 120 in instances when the apertures *p* do not reg- 125

ister with exactness with the center line of the apertures *k* of the planks.

In the modified form of the invention shown in Fig. 13, the inclined depressions or recesses *e* are the same as already described, the cutting edges or the blades *f'*, however, extending completely to the lower side of a bolt-head *a*, a secondary recess *c'* being provided in the wall of the recess *b* to permit engagement therein of a projection *d* of the cap 15, this modified form being considered clearly within the scope of the invention since the function for the secondary recesses *c* and *c'* are identical, and it is not important which side of the recesses *b* the secondary recesses *c* and *c'* are located, the function to be discharged by these recesses being simply to operate as detaining elements, so that, during operation, the cap 15 will not become accidentally detached from the bolt-head. Also it will be noted that the upper, inclined walls of recesses *e* may discharge the same function as recesses *c* or *c'*.

25 I claim as my invention,—

1. In devices for the purpose described, the combination with a bolt having a head provided with peripheral recesses, said head being provided on its inner side with secondary recesses each opening on a peripheral recess and with radially disposed blades each extending from the shank to terminate in a recess, the side wall of each secondary recess providing a second blade disposed in the plane of a first named blade, of a revoluble cap having lugs provided with projections, the combined widths of each lug and its projections being less than the width of a peripheral recess to permit said cap to be disposed with its lugs engaging in the peripheral recesses with one of its projections engaging in a secondary recess of said head.

2. In devices for the purpose described, the combination with a bolt having a threaded terminal and having a head circular in plan provided with peripheral recesses opening on its top and bottom, each recess having a terminal wall between said periphery and center of said head and one of the walls of each peripheral recess having a secondary recess opening thereon, of a rotatable cap having lugs provided with projections, said cap being adapted to be disposed with its bottom engaging the top of said head with its lugs engaging in the peripheral recesses of said

head, a projection of each lug engaging in a secondary recess thereof, the combined widths of each lug and its projections being less than the width of a peripheral recess.

3. In devices for the purpose described, the combination with a bolt having a head provided with peripheral recesses and secondary recesses, each secondary recess opening on a peripheral recess, and provided in its inner side with blades disposed radially to terminate in the secondary recesses, the side wall of each secondary recess providing a second blade disposed in the plane of a first named blade, of a rotatable cap having lugs projecting from its inner side, each lug being provided with a projection, the combined widths of each lug and its projection being less than the width of a peripheral recess to permit the lugs to be inserted in said peripheral recesses for engagement of the projections in said secondary recesses.

4. In devices for the purpose described, the combination with a bolt having a head of disc-form provided in its periphery with a recess and a second recess opening on the first named recess, of a revoluble cap having a head formed angular in plan and having a lug provided with a projection and adapted to be disposed with its lug engaging in the first named recess, the projection of said lug engaging in the second recess, the combined widths of the lug and its projection being less than the width of said first named recess.

5. In devices for the purpose described, a cap provided with a head angular in plan and having a lug provided with a projection and extending from its bottom, a bolt having a threaded terminal and having a head circular in plan provided in its inner side with radially disposed blades and having a recess opening on its top and bottom for receiving the lug of the cap and having a second recess opening on the first named recess for receiving the projection of said lug, the side wall of the second recess providing a blade disposed in the plane of the first named blades, the combined widths of said lug and its projection being less than the width of said first named recess.

In testimony whereof, I have affixed my signature in presence of two witnesses.

ROBERT Z. DRAKE.
